UNITED STATES PATENT OFFICE.

LOCKE H. BURNHAM, OF PITTSFIELD, MASSACHUSETTS, ASSIGNOR TO GENERAL ELECTRIC COMPANY, A CORPORATION OF NEW YORK.

FORCED OIL TRANSFORMER.

Application filed February 27, 1922. Serial No. 539,650.

To all whom it may concern:

Be it known that I, LOCKE H. BURNHAM, a citizen of the United States, residing at Pittsfield, county of Berkshire, State of Massachusetts, have invented certain new and useful Improvements in Forced Oil Transformers, of which the following is a specification.

My invention relates to electric transformers and more particularly to an improved construction and arrangement of parts adapted to prevent the occurrence of undesirably high temperatures within such transformers. When a transformer is operating under load, heat is generated in the core and windings which assume temperatures dependent upon the amount of heat generated and upon the rate at which the heat is removed from them. Obviously, the more rapidly this heat is removed from the transformer parts, the greater will be the load which the transformer can carry for a given maximum rise in temperature. The general object of the present invention is to provide an improved construction whereby the heat generated in a transformer may be rapidly and efficiently removed so that the transformer may be heavily loaded without danger of its being subjected to undesirable temperatures.

Transformers are often immersed in an insulating fluid such as a suitable oil having high dielectric strength. This fluid penetrates the openings and interstices of the transformer and serves not only as insulation but also as a heat absorbing medium. It is important, however, that the fluid be not only permitted to reach all heated parts of the transformer but also that it be free to circulate readily so as to carry away rapidly the heat which it has absorbed from those parts. One of the objects of the invention is to provide a transformer immersed in an insulating and cooling fluid and so constructed that currents of the fluid will be thoroughly distributed among and through these parts. A further object of the invention is to provide an improved means for supplying the cooling fluid to the transformer.

In order to illustrate the principles of the invention, one embodiment thereof is shown in the accompanying drawing in which Fig. 1 is a view in elevation of a three

phase transformer with a cooling system 55 constructed in accordance with the invention, the view being partly in section to show details of construction; Fig. 2 is a plan view of the transformer and cooling system shown in Fig. 1; Fig. 3 is a perspective view of a 60 detail of the cooling system; and Figs. 4 and 5 are elevations of spacing members used in the coil stacks of the transformer.

Like reference characters refer to similar parts in the different figures of the drawing.

In the particular embodiment of the invention shown in the drawing, a three phase transformer including a three legged core 1 with windings 2 on each leg is enclosed in a 70 tank or casing 3 adapted to hold a body of insulating and cooling fluid 4 in which the transformer is immersed. The stack of windings 2 on each leg are of the interleaved disc coil type. Each coil is enclosed in a 75 casing or wrapping 5, the casing on each coil being spaced from one or both faces of the coil by a flat annular insulating disc 6 which is in turn spaced from the face of the coil by radially disposed spacers 7 formed 80 with transverse openings or notches 8 as indicated in Fig. 2 and as shown clearly in Figs. 4 and 5. By this arrangement, each set of spacers 7 serves to maintain a series of radially disposed spaces 9 between each 85 of the annular discs 6 and the adjacent coil surface, these radially disposed spaces being all connected together by the openings or notches 8 in the spacers 7.

A fluid conductor or pipe 10 is supported 90 longitudinally of each coil stack and along its outer face. The side of each pipe 10 toward the coil stack is provided with a slot or opening 11 opposite which the casing or wrapping 5 is removed from the coils comprising the winding 2, thus providing entrance openings from the pipes 10 to the spaces 9 between the annular discs 6 and the coils. Another narrow longitudinal section 95 of each casing 5 is also removed from each coil stack, preferably substantially opposite the pipe 10 in each case, thus forming exit openings 12 from the spaces 9 to the main body of fluid 4 surrounding the coil stacks. One end of each of the pipes 10 is connected 100 to a supply pipe 13 with a fluid pump 14, the opposite ends of the pipes 10 being closed.

Oil or other insulating and cooling fluid supplied under pressure from the pump 14 will flow through the pipe 13 and the pipes 10 into and through all the spaces 9, finally emerging from the coil stacks through the openings 12 and mingling with the main body of fluid 4 surrounding the windings in the tank 3. From the casing 3, the fluid is conducted back to the intake of the pump 14 through pipes 15 and a cooler 16. This cooler is shown as comprising an outer casing through which the fluid flows and an enclosed coil of pipe 17 adapted to conduct a cooling current of some suitable fluid such as water to reduce the temperature of the current of warmed fluid returning from the transformer to the pump.

In order that the current of cooling fluid passing through the coil stacks of the transformer may be thoroughly distributed over the surfaces of the transformer coils, the openings or notches 8 in the spacers 7 may be disposed in staggered relation in successive spacers as indicated in Fig. 2 and also in Figs 4 and 5, these latter figures showing two successive or adjacent spacers removed from one of the transformer coil stacks. Another advantage attained by staggering the notches 8 is the assurance of support for each turn of the coil at least as often as at every second spacer. The turns of the conductor are of course substantially concentric with the axis of the coil and it is obvious that, with the notches 8 staggered in successive spacers, any turn of the coil which lies opposite a notch in one spacer will escape the notches in the next spacer in either direction. A set of spacers 7 is provided for both faces of each winding coil except that, as indicated in Fig. 1, the spacers may be omitted if desired from the outer face of each end coil. Here, the coil surface is separated from the main body of cooling fluid 4 only by the casing or wrapping 5

which may permit sufficient cooling of this coil surface.

In the particular construction shown in the drawing, the openings 12 through which the cooling fluid leaves the coil stacks are all disposed so that the fluid is discharged from the stacks at one side of the tank 3 and the pipes 15 are so disposed that the fluid leaves the tank from convenient points at the opposite side of the tank after flowing along the outer surfaces of the coil stacks.

What I claim as new and desire to secure by Letters Patent of the United States, is:—

1. The combination with a transformer of an enclosing tank containing cooling fluid in which the transformer is immersed, said transformer including a plurality of disc coils, radially arranged spacers between said coils, said spacers being constructed and arranged with openings respectively staggered in adjacent spacers, means enclosing said coils and spacers, said enclosing means having entrance and exit openings to permit the cooling fluid to enter and leave the spaces between the coils, means including a fluid cooling device outside said tank, and means for conducting cooling fluid from said cooling device to said entrance openings and from said tank back to said cooling device.

2. The combination with a transformer of an enclosing tank containing cooling fluid in which the transformer is immersed, said transformer including a plurality of disc coils, each of said coils having spacers between one of its faces and the adjacent coil, each coil and its spacers being enclosed in an individual casing having entrance and exit openings for cooling fluid, and means for conducting cooling fluid to said entrance openings.

In witness whereof, I have hereunto set my hand this 24th day of Feb., 1922.

LOCKE H. BURNHAM.
